GLOVE

Sarah Lipton, New York, N. Y.

Application July 7, 1936, Serial No. 89,299

11 Claims.

(Cl. 2—162)

This invention relates to gloves, and more particularly to means for effecting a snug and secure fit of a glove around the wrist of the wearer while producing an ornamental gathered effect.

To this end provision is made of a piece of elastic which is disposed to extend transversely of the glove at the wrist portion and which is secured to the glove at its ends.

More specific features of the invention have to do with means for detachably securing the elastic in place, as by means of buttons, and with means for providing a double lock for the buttons.

Other features of the invention have to do with ways of mounting and covering the elastic so as to produce desired effects.

Other objects and advantages will hereinafter appear.

The present application is a continuation in part of my pending application Serial No. 71,828 filed March 31, 1936 for Wearing apparel.

In the drawings forming part of this specification and showing certain preferred embodiments of the invention,

Fig. 1 is a view in front elevation of a glove embodying one form of the invention;

Fig. 2 is a sectional view taken on the line 2—2 of Fig. 1 looking in the direction of the arrows;

Fig. 3 is a fragmentary view in front elevation of a second embodiment of the invention;

Fig. 4 is a fragmentary sectional view taken on the line 4—4 of Fig. 3 looking in the direction of the arrows;

Fig. 5 is a fragmentary sectional view taken on the line 5—5 of Fig. 3 looking in the direction of the arrows;

Fig. 6 is a fragmentary view in front elevation showing a third embodiment of the invention;

Fig. 7 is a fragmentary sectional view taken on the line 7—7 of Fig. 6 looking in the direction of the arrows;

Fig. 8 is a fragmentary view in elevation showing a fourth embodiment of the invention;

Fig. 9 is a fragmentary sectional view taken on the line 9—9 of Fig. 8 looking in the direction of the arrows;

Fig. 10 is a fragmentary view in front elevation showing a fifth embodiment of the invention, and

Fig. 11 is a fragmentary sectional view taken on the line 11—11 of Fig. 10 looking in the direction of the arrows.

In the form of the invention disclosed in Figs. 1 and 2 a glove 1 has applied to its inner face transversely of the wrist portion a narrow ribbon or tape 2 of flexible fabric. The fabric is

tacked to the glove material at a number of equally spaced points 3 along its opposite margins and is stitched to the glove material at its ends. The ribbon forms, with the body of the glove, an enclosure for receiving a strip of elastic 4. The ends of the elastic are passed around central cross bars 5 of slides 6 and tacked by stitching 7. The ribbon 2 is provided with transverse slits 8 near its ends which are desirably worked as buttonholes to prevent the edges from fraying. The elastic 4 is normally of less length than the distance between the slits 8 so that when the elastic is inserted the glove and ribbon material is caused to gather.

The elastic is put in place by inserting one of the slides 6 through one of the slits 8, then across the passage between the ribbon and the glove body and through the other slit 8. The slides act as buttons to retain the elastic in place. The elastic serves to gather the glove material between the ends of the elastic and thereby to reduce the length of the glove periphery at the wrist portion while leaving the same free to be extended. The spaced tacks 3 cause the glove material to be gathered in a series of neatly arranged folds or puckers.

When the gloves are to be cleaned the elastic can be readily removed from them by unbuttoning one of the slides and drawing it out through the slit 8 at the opposite end of the passage-way from that at which it is normally located in use.

In the form of the invention disclosed in Figs. 3 to 5 a glove 1a has a ribbon 2a stitched at its ends to the outer face of the glove and tacked by stitches 3a at intervals along one margin of the ribbon. A piece of elastic 4a provided with slides 6a at its ends is threaded through a series of slits 9 which are formed in the glove material 2a. An even number of slits 9 is desirably provided so that the slides may be received in the space between the ribbon and the glove material. The elastic and the slides are concealed by the ribbon, and the wearer's wrist is protected from contact with the slides by the interposed material of the glove body. When it is desired to remove the elastic, access to it may be had by folding back the ribbon, which is free along one margin.

In the form of the invention disclosed in Figs. 6 and 7 a glove 1b has a ribbon 2b tacked by stitches 3b located at uniform intervals to its outer face. The ribbon is provided with buttonholes 10 at its opposite ends and with additional openings 11 adjacent the buttonholes. An elastic band 4b is provided with buttons 6b at its opposite ends. Elastic cords 12 are stitched to

the elastic band to form loops. The elastic band is first inserted and buttoned in the same manner as the elastic band of Figs. 1 and 2. The elastic loops 12 are then drawn through the openings 11 and passed around the associated buttons 6b. The elastic loops form a secondary or safety lock for the buttons 6b and thereby serve both to assure the retention of the buttons in place and to relieve the buttonholes of strain.

10 In the form of the invention disclosed in Figs. 8 and 9 the glove 1c has a ribbon 2c tacked to the inner face of the glove material and disposed at the inner side of the glove. The tacking stitches are provided only along one margin of the ribbon 2c. A piece of elastic 4c has buttons 6c connected to its ends through inelastic loops or cords 13. The buttons are adapted to be passed outward through buttonholes 10c formed in the glove material. Locking tabs 14 are 20 stitched to the ends of the elastic 4c and each may be passed around the associated end of the elastic through the associated loop 13 and out through an opening 15 formed in the glove material. Each tab 14 is provided with a buttonhole 25 16 adapted to be buttoned over the associated button 6c. It is desirably made of an attractive fabric which harmonizes with the material of the glove.

In the form of the invention shown in Figs. 10 30 and 11 a glove 1d is provided with a series of parallel slits 9d. A piece of elastic 4d is enclosed in a fabric sheath 17. Buttons 6d are secured to the ends of the sheathed elastic and are adapted to be passed outward through buttonholes 10d 35 formed in the glove material. Locking tabs 14d are stitched to the outer side of the sheath 17 and each is adapted to be passed outward through one of the slits 9d and to be buttoned to the associated button 6d by means of a buttonhole 16d 40 with which the tab is provided. The sheathed elastic is threaded through the glove material between the buttonholes 10d, being passed through each of the slits 9d so that it overlies alternate strips of glove material. The sheath 17, as well 45 as the tabs 14d, are desirably formed of a fabric which harmonizes with the glove material.

While I have illustrated and described in detail certain preferred forms of my invention, it is to be understood that changes may be made 50 therein and the invention embodied in other structures. I do not, therefore, desire to limit myself to the specific constructions illustrated, but intend to cover my invention broadly in whatever form its principle may be utilized.

55 I claim:

1. In a garment, the combination with the garment material, of an elastic band extending girthwise at one side of the garment to produce a gathering of the material, buttonholes set girthwise in the garment body member at a distance apart greater than the length of the unextended elastic buttoning members carried by the elastic band at opposite ends thereof for detachably connecting the elastic band in place, and button locking members carried by one of the elements 60 for interlocking with the buttoning members after the buttoning members have been buttoned in place.

2. In a garment, the combination with the 70 garment material, of an elastic band extending girthwise at one side of the garment to produce a gathering of the material, buttoning members carried by the elastic at opposite ends thereof, button locking members carried by the elastic band for interlocking with the buttoning mem-

bers after the buttoning members have been buttoned in place, and a strip of fabric stitched at intervals to the garment material and forming with the garment material a space along which the elastic band extends.

3. In a garment, the combination with the garment body member, of a fabric member secured to the body member girthwise at one side of the body member, one of said members being provided with a plurality of parallel slits, an 10 elastic band threaded through said slits, buttonholes set girthwise in one of said members at a distance apart greater than the length of the unextended elastic, buttoning members carried at the ends of the elastic band for detachably securing the band ends to one of said members, and button locking members carried by the elastic band for interlocking with the buttoning members after the buttoning members have been buttoned in place.

4. In a garment, the combination with a garment body member, of a fabric member secured girthwise to the body member at one side thereof, one of said members being provided with a pair of buttonholes, an elastic band disposed to 25 extend girthwise between said members, buttoning members carried by the elastic band and adapted to be buttoned through said buttonholes to gather the material between the buttonholes, and button locking members carried by the elastic band for interlocking with the buttoning members after the buttoning members have been buttoned in place.

5. In a garment, the combination with a garment member having buttonholes at spaced 35 points girthwise of the member, and additional openings adjacent said buttonholes, of an elastic band, buttons carried by the ends of the band and adapted to be passed through the buttonholes, and locking members also carried by the 40 band and adapted to be passed through said additional openings and then around the buttons.

6. A structure as set forth in claim 5 wherein the locking members are in the form of elastic loops.

7. A structure as set forth in claim 5 wherein the locking members are in the form of fabric tabs having buttonholes worked in them.

8. In a garment, the combination with a garment body member, of a fabric ribbon stitched to 50 said member girthwise across the outer face thereof, an elastic band threaded through the body member in the area covered and concealed by said ribbon, buttonholes set in the garment body member spaced girth-wise at specified points 55 in relation to the elastic band, buttoning members carried by the ends of said elastic band for detachably securing the band to the glove body member, and button locking members carried by the elastic band for interlocking with the buttoning members after the buttoning members have been buttoned in place.

9. In a garment, the combination with a garment body member, of a fabric ribbon tacked at intervals to said body member girthwise thereof, 65 said ribbon having buttonholes worked in its ends and additional openings worked adjacent said buttonholes, an elastic band disposed in the space covered by the ribbon, buttons carried by the ends of the elastic band, and elastic locking loops 70 carried by the elastic band, each adapted to be passed through one of said additional openings and around the associated button.

10. In a garment, the combination with a garment body member having buttonholes worked 75

therein and an additional opening adjacent each buttonhole, of a fabric strip tacked at intervals to the inner face of the body member, an elastic band, buttons at the ends of the elastic band for 5 cooperating with the buttonholes, and locking tabs carried by the elastic band, each adapted to be brought out through one of the additional openings and buttoned to the associated button.

11. In a garment, the combination with a garment body member having a portion thereof 10 provided with a pair of girthwise spaced button-

holes and the part between the buttonholes divided by parallel slits, of an elastic band, a sheath enclosing the elastic band, buttons carried by the ends of the elastic band, and locking tabs carried by the sheath, the sheathed elastic band being threaded through the slitted material of the garment body and buttoned to the garment body at its ends, and each of the locking tabs being brought out through one of the slits and buttoned to the associated button. 10

SARAH LIPTON.
